DESIGN FOR A COMBINED HOLDER FOR CIGARETTES AND MATCHES

Loretta M. Provost, Glendale, Calif.

Application January 19, 1945, Serial No. 117,501

Term of patent 3½ years

(Cl. D48—28)

To all whom it may concern:

Be it known that I, Loretta M. Provost, a citizen of the United States of America, residing at Glendale, in the county of Los Angeles and State of California, have invented a new, original, and ornamental Design for a Combined Holder for Cigarettes and Matches, of which the following is a specification, reference being had to the accompanying drawing, forming part thereof.

Fig. 1 is a front elevational view of a combined holder for cigarettes and matches showing my new design;

Fig. 2 is a side elevational view; and,
Fig. 3 is a perspective view thereof.

I claim:

The ornamental design for a combined holder for cigarettes and matches, as shown.

LORETTA M. PROVOST.
